UNITED STATES PATENT OFFICE.

JAMES HIGGINSON, OF NEW BEDFORD, MASSACHUSETTS, ASSIGNOR OF ONE-HALF TO
ARCHIBALD S. FULLER, OF NEWTON, MASSACHUSETTS.

STOP-MOTION FOR TEXTILE-MACHINES.

1,303,664.

Specification of Letters Patent. Patented May 13, 1919.

Application filed August 4, 1917. Serial No. 184,477.

To all whom it may concern:

Be it known that I, JAMES HIGGINSON, a citizen of the United States, and resident of New Bedford, in the county of Bristol and 5 State of Massachusetts, have invented new and useful Improvements in Stop-Motions for Textile-Machines, of which the following is a specification.

This invention relates to stop motion devices for lapping, drawing, doubling or other textile machines treating a fleece or sliver of fibrous material, and especially to machines of this nature adapted to draw by progressively increasing-speed sets of rollers 15 an attenuated lap, fleece or sliver.

It has heretofore been the practice to provide machines of the class indicated with mechanically actuated stop motions comprising power-release means and a detector 20 device actuated upon breakage or running out of the sliver, lap or fleece, prior to its entrance upon the bank of drawing-rolls, railway-head, or the like; and for some kinds of material, it has been possible to 25 actuate the stop motion by breakage of the material after it has been drawn, or between the sets of drawing-rolls. It has also been proposed to detect in such machines the elevation of one or more of the drawing-rolls 30 due to the winding of an end or a loop of the sliver, lap or fleece about said roll, which sometimes occurs when one part of the material under treatment presents a broken or loose loop, continued operation of the machine 35 when causing breakage of the machine as well as defective product, but such devices as last mentioned are not in general use, perhaps because of defects of construction and lack of reliability in operation.

The present invention provides improved means coöperating with the existing broken or run-out lap stop-motion devices to occasion stoppage of the whole machine or of the particular set of drawing-rolls affected 45 whenever any part of the material under treatment laps about or is wound upon any of the drawing-rolls forming a part of the existing machine. Objects of the invention are to provide a wholly reliable device of 50 this character capable of being attached with a minimum of effort, expense and skill to existing machines, and to provide for the sensitive operation of the device immediately upon the beginning of winding upon 55 all or any part of one or more of the rolls

of a broken part or loose loop of an attenuated sliver or lap. Other objects are to provide such a stop motion device enabling the rolls to be examined, changed, or cleaned readily without removing the stop motion 60 device.

In the accompanying drawings,

Figure 1 is a typical section, showing one bank of drawing rolls of a ribbon lap machine with the new device in place; 65

Fig. 2 is a similar fragmentary view showing one detector, the connection therefrom, and a part of the power release device when the machine has been stopped by the occurrence of the fault for which it is desired 70 to stop the machine;

Fig. 3 is a plan, the drawing rolls being removed;

Fig. 4 is a rear elevation, parts being broken away; and 75

Fig. 5 is a section on an enlarged scale on line 5—5 of Fig. 3.

Referring to Fig. 1, the ball or wound lap 1 of material to be drawn is supported as usual on the rolls 2, the sliver or fleece 3 80 passing over the table 4 through guides 5, over the respective bottom rolls 7 and under the respective top rolls 8 of the drawing-rolls, as shown. As usual in the art, bearings 9 for the rolls 7, 8, may be open slots 85 giving upward freedom of movement to both rolls. The respective pairs of rolls 7, 8, are driven at progressive speeds, as usual.

The top rolls are maintained at a constant pressure upon the fleece or sliver being drawn by the weight-hooks or yokes 10; as usual in the art, said yokes supporting, as by links 11, and in the plane of the axes of the rollers, the weights 12. 90

For one specific instance only of the existing stop motion device with which the new devices are intended to coöperate, Figs. 1 and 2 illustrate a flat detector guide or spoon 13 as mounted on a lever 14, Figs. 1 and 2, projecting through an aperture 15 in the table 4. The lever 14 is pivoted on a knife-edge 16 so that the counterbalance weighted balk 17 tends to raise the detector guide 13, except when the guide 13 is depressed by the weight 105 of the lap or sliver 3.

The balks 17 when permitted to drop are caught between the teeth of a rotating spider 19 and frame-member 18 so as to stop the spider 19 and the spider shaft 20, Figs. 1 110

and 4. As shown in Fig. 4, the shaft 20 may be driven by a gear 21 through a cam-faced clutch 22 normally held together by a weighted lever 23, adapted when displaced 5 by the stoppage of the shaft 20 to lift a notched belt-shipper rod 24 from its engagement at 25 with a member of the frame. Rod 24 is provided with a spring, not shown, to shift the belt. The said broken-lap or 10 run-out-lap detector and stopping device 13, 20, 24, etc., is typical of the old art and forms no part of the present invention except as hereinafter explained.

In order to adapt such devices also to stop 15 the machine when any part of the material under treatment winds upon any one of the rolls 7 or 8, provision is made to lift the existing detector element, as 13. In the form shown, a connection between the yokes 10 20 and detector 13 is provided. This connection may comprise a pair of rocker bars 30, 31, preferably pivoted by perforated lugs 32 on a fixed shaft 33 hung in bearing brackets 34 bolted to the machine frame at 35 and 25 extending under each bank of drawing-rolls.

The rocker bars 30, 31 each carry arms 36, which may be integral with the respective frames, and which lie in the vertical plane of the last pair or front drawing-rolls 7, 8, the 30 arms 36 resting upon the yokes 10 or links 11 so that at least one of the arms 36 will be moved by motion of the weight yoke 10 at either or both ends of the roll induced by lifting the roll 8, which will occur when the 35 material under treatment winds upon any part of either the roll 7 or the roll 8. The arms 36 can be integral because the weight yokes 10 for the front drawing-rolls can be swung forward to release the rolls of their 40 weight, arms 36 not interfering with this operation. The respective bars 30, 31, which are preferably rectangular in section, also carry arms 37 having slotted bosses 38, Fig. 4, to take over the respective frames, and 45 having if desired adjustment screws 39, each arm 37 being in the plane of a pair of drawing-rolls so as to rest upon the link 11 or the weight yoke 10.

Rigid, and preferably integral, with the 50 bar 30 is an arm 40, the bar 31 having a similar arm 41. These arms as shown in Fig. 1 extend upwardly at the rear of the frame carrying the drawing-rolls, and are connected by a linkage having members 42, 43, pivot- 55 ed together and to the respective arms 40, 41, as by shouldered pivot screws 44, 45, the members 42, 43, having large bosses 46 to prevent the lazy-tong linkage 40, 41, 42, 43 from closing upon itself too tightly. As shown in 60 Figs. 4 and 5, the linkage is adjustable to vary the elevation of yokes 10 at which the machine stops, as by varying the position of the pivot screws 45; levers 42 and 43, for instance, being slotted at 50 to receive 65 threaded and headed shoulder screws 45 ad-

justably held by nuts 52 in the slots 50. The members 42, 43, terminate in enlargements 48, which normally stand under the detector guide 13 as best shown in Figs. 1 and 4.

The operation will now be apparent. If 70 any of the rolls 7, 8, are wound upon at any part of their length, either or both the bars 30, 31, will be rocked on the shaft 33, causing the arms 40, 41, to approach each other, which movement is transformed into elevation of the enlargements 48, 48, at a greatly multiplied rate, a slight displacement of either frame resulting, by reason of the linkage 40, 41, 42, 43, in a large upward movement of the detector 13, and prompt stop- 80 page of the machine by the intervention of the lever 14, balk 17, spider 19 and the devices actuated thereby. The arms 37 may be lifted from the bars 30, 31, whenever it is necessary to remove a top roll 8, and replaced without altering the adjustment of screws 39, which are not tightened on the respective bars.

What I claim is:

1. A stop-motion device for textile machines comprising a breakage or absent-material detector, a power release device worked thereby, means for detecting displacement of a roll acting on the material under treatment, and an operating connection from said displacement detecting means to said breakage detector. 90

2. A stop-motion for textile machines having pairs of drawing-rolls comprising power release devices and an independent connection between said devices and the ends of one member of each pair of rolls, said connections being linked together whereby to multiply the motion at either end of said rolls effective to operate said power release 100 devices. 105

3. A stop-motion for a machine having drawing-rolls comprising power release devices, means for detecting displacement from normal position of one or more of said rolls, 110 and a connection between said devices and said means comprising a plurality of rocker-bars, and a linkage between said bars adapted to actuate said release devices upon movement of one or more of said bars. 115

4. A stop-motion for textile machines having a plurality of rolls, comprising power release devices, means for detecting displacement from normal position of any of the rolls acting on the material under treatment, 120 and a connection between said devices and said means comprising a linkage adapted to multiply to like extent the displacement of said displacement detecting means caused by displacement of any of said rolls. 125

5. A textile machine stop-motion adapted to be actuated by material under treatment winding about a bodily movable roll working on the same, having therein independent detector means coöperating with each bear- 130

ing end of said roll, said means being independently movable by motion at either end of said roll, and a connection between the detector devices for the respective ends of said roll adapted to multiply the motion of either detector device, and means operated by said connection for releasing the power.

6. A textile machine stop-motion having power release devices, detector means for a wound-upon roll, and a connection between said devices and said means comprising a lazy-tong linkage adapted to multiply the motion of displacement of said roll.

7. A textile machine stop-motion comprising displaceable rolls acting on the material under treatment, power release devices adapted to be actuated by a detector acting on said material, and means adapted to be attached to the machine comprising rocker-bars respectively having arms reaching to a

part displaceable with said rolls, and a linkage between said bars adapted to actuate said detector upon movement of any or all of said rocker-bars.

8. A textile machine stop-motion comprising displaceable rolls acting on the material under treatment, power release devices adapted to be actuated by a detector acting on said material, and means adapted to be attached to the machine comprising rocker-bars respectively having arms reaching to a part displaceable with said rolls, and an adjustable linkage between said bars adapted to actuate said detector upon movement of any or all of said arms to a predetermined extent. 25 30 35

Signed by me at Boston, Massachusetts, this 3rd day of July, 1917.

JAMES HIGGINSON.
